ABSTRACT

An oscillating brush device comprising a pair of racks which are driven in reciprocation as is a gear mounted on the brush shaft. The racks are slotted at one end and receive eccentric cams mounted on a worm wheel to impart the desired reciprocation of the brush.

1 Claim, 4 Drawing Figures

PATENTED FEB 11 1975

OSCILLATING BRUSH

This invention relates to motor driven tools and, in particular, to rotative brushes used for example, to scour and clean pots and pans.

The invention contemplates an oscillating brush the reciprocating motion of which provides enhanced efficiency in dislodging particles on pots and pans which have been stuck to the cooking surfaces under high temperatures and in some cases pressures. The present oscillating brush has proven highly efficient in comparison with the ordinary rotary brush and hand scouring.

One object of the invention is to provide an improved motor-driven brush device.

Other objects and advantages of the invention may be appreciated on reading the following description of an embodiment thereof which is taken in conjunction with the accompanying drawings, in which:

FIG. 1 is a perspective view of the invention;

FIG. 2 is an enlarged side view with parts broken away to show the arrangement of the drive means;

FIG. 3 is a horizontal sectional view showing the worm drive and reciprocating means and taken on the line 3-3 of FIG. 2; and

FIG. 4 is a cross-sectional view and taken on the line 4-4 of FIG. 2.

Referring to the drawings and, more particularly to FIG. 1, there is shown a pot and pan cleaning brush 10 comprising a handle 12, a housing 14 for the drive means employed to oscillate brush 16. The handle 12, which is hollow, is provided with a motor 18 powered by battery 20 and actuated by the switch 22.

A worm screw 24 mounted on the armature shaft of motor 18 is in driving engagement with a worm wheel 26 on shaft 28, which in turn is supported by bearing brackets 30 and 32 fixed in the handle 12.

Eccentrically mounted on opposite sides of the worm wheel 26 are cams 34 and 36. A pair of symmetrical reciprocating members 38 and 40 having cam follower slots 42 and 44 engaging the eccentric cams 34 and 36, 40

respectively, which are in opposite phase to impart reciprocal motion to the members. The reciprocating members 38 and 40 are provided with racks 46 and 48 on the inner edges of their free ends. Pinion 50 mounted on shaft 52 engages on opposite sides thereof the racks 46 and 48. The arrangement is such that the pinion 50 is oscillated in a strain free manner about its axis by the simultaneous push-pull action of the racks 46 and 48.

10 As best seen in FIG. 4, the members 38 and 40, with their racks 46 and 48, are guided and maintained in engagement with the pinion 50 by a platform 54 having rails 56 and 58. A top plate 60 is supported on posts 62 and 64 fixed to platform 54 to guide the top edges of members 38 and 40.

The pinion shaft 52 extends below the housing 14 and terminates in a retaining socket 66 to accommodate a half-round stud 68 for driving the brush 16 in oscillation being held therein by C-spring 70, thus permitting its replacement or the use of other types of brushes.

Various modifications of the invention may be appreciated by persons skilled in the art without departing from the scope and principle of the invention as defined in the appended claims.

What is claimed is:

1. An oscillating brush device comprising a housing, a pinion shaft mounted in said housing and extending therethrough, a brush secured to the pinion shaft outside said housing, a pinion mounted on the shaft within the housing, a pair of racks engaging said pinion respectively on opposing sides thereof, a motor mounted in said housing and having a rotary drive shaft, a worm screw in driven connection with said shaft, a worm wheel engaging said worm screw, a cam mounted on each face of said worm wheel in opposite phase, each of said racks being operatively connected to one of said cams whereby oscillatory motion is imparted to said brush upon rotation of said shaft.
